DESIGN FOR A COFFEE BREWER

Hoyt K. Foster, Hollis, N. Y., assignor to S. W.
Faber, Inc., Brooklyn, N. Y.

Application March 28, 1942, Serial No. 106,358

Term of patent 14 years

To all whom it may concern:

Be it known that I, Hoyt K. Foster, a citizen of the United States, residing at Hollis, in the county of Queens and State of New York, have invented a new, original, and ornamental Design for a Coffee Brewer, of which the following is a specification, reference being had to the accompanying drawing, forming part thereof, wherein:

Figure 2 is a fragmentary side elevational view of the coffee brewer of Fig. 1. Both the upper and lower bowls of the coffee brewer are circular in cross section.

I claim:

The ornamental design for a coffee brewer, substantially as shown and described.

HOYT K. FOSTER.
